COMBUSTION AIR FEEDING STRUCTURE
FOR OIL-BURNING LOCOMOTIVESVaughn Mansfield, Whitehaven, Tenn., assignor
to Mansfield Engineering Company, Memphis,
Tenn., a limited partnership of Tennessee

Application June 30, 1947, Serial No. 758,060

2 Claims. (Cl. 110—76)

1

This invention relates to air feeding systems and, more particularly, to apparatus for feeding air to the combustion chamber of an oil fired locomotive.

The primary object of this invention is to overcome the deleterious effects of the air stream passing a locomotive. In the usual locomotive, air is taken, through various inlets, into the combustion chamber for burning with the oil, the hot combustion gases then passing forwardly through the boiler tubes to the smoke box. Exhaust steam from the cylinders is utilized for inducing, through a nozzle, the outflow of combustion products from the smoke box. It is thus apparent that the amount of air flowing through the combustion chamber depends primarily on the contrast in pressures between the air inlets and the exhaust nozzle, and disproportionately high steam pressures have heretofore been necessary for inducing the necessary contrast, resulting in high back pressures in the cylinders. Since the power output of the locomotive depends upon the mean effective cylinder pressure, overall efficiency depends to a surprisingly large extent on the cylinder back pressure required for inducing the air flow into the fire box. It has been found that turbulence in the fire box is essential to proper combustion of the oil and that an unusually high pressure differential has to be maintained at the air inlets to create the desired furnace turbulence. The necessity for the unusually high differential at the conventional air inlets is created by the deleterious effects of eddy currents and wind velocities upon the side air inlets, rearwardly disposed air inlets, and because of confusing blasting by air from forwardly disposed inlets. The object now is to enshroud the lower portion of the fire box of an oil fired locomotive with a plenum chamber, and to feed air, with minimum turbulence, to the plenum chamber. By this invention it is intended to assure proper distribution of air to the firebox through various air openings of an oil fired locomotive firebox.

These and other objects will be apparent from the following specification and drawings, in which:

Fig. 1 is a vertical longitudinal section through the fire box of an oil burning locomotive embodying the invention taken substantially along the line 1—1 of Fig. 2 looking in the direction of the arrows; and, Fig. 2 is a vertical transverse section taken along the line 2—2 of Fig. 1 looking in the direction of the arrows.

Before describing the invention, the structure typifying the fire box 2 of a typical locomotive

2

4 will be briefed. This includes a boiler shell having side walls 6, pan 8 lined with fire brick 10, a flash wall 12 at the back end, lower and rear walls 14 and 16 of the boiler shell and an oil burner 18 which may partake of any one of several forms and be variously located. While various arrangements of air inlet openings occur, they generally include a set of forwardly directed apertures 20, air inlet tubes 22 through each side wall, a rearwardly opening hopper 24 having an adjustable damper controlled, rearwardly facing opening 26, rearwardly directed inlets 28 through flash wall 12 connecting the interior of fire box 2 with an air space 30 open to the atmosphere 15 behind the blank wall, and an air inlet 32 connecting via opening 34. Combustion products pass upwardly towards top 36 of the boiler shell and forwardly to the smoke box (not shown) through tubes 38. Generally, side inlet tubes 22 20 have a flash guard (not shown) spaced beyond their outer ends.

While the locomotive thus far described is standing or running at low speed, fairly uniform air entrance and distribution occurs. At high speeds, or with a strong head wind, and cross winds, air blasts through frontal openings 20, shoots by side inlet tubes 22, and the physical obstructions in front of openings 26 and 28 interfere with proper air flow into the fire box through 30 these ports.

The invention comprises a plenum chamber 40 having an outer casing 42 surrounding the lower portion of fire box 2 and enshrouding openings 20, 22, 26 and 28. Air is fed to chamber 40 35 through a trough 44 having a series of transverse baffles 46 spaced therealong and preferably extending across the trough and within the gap 48 between the lower edge of the mud ring 50 and trough bottom 52. One arrangement of the 40 trough and baffles is disclosed in prior Mansfield Patent 2,415,256.

In the drawings the upper ends of the baffles 46 are shown bent in a forward direction in order to facilitate scooping in of air, however, if desired, 45 these baffles may be made straight as shown in my prior Patent 2,415,256, granted February 4, 1947. The baffles 46 are also shown in the drawings as extending to the bottom 52 of the trough 44, but it is evident that they may be made to 50 stop short of the bottom of the trough 44 in accordance with the construction shown in my prior patent, referred to above.

It should be noted particularly that the effective height of baffles 46 increases from front to 55 rear so that each baffle, except the first, overlaps

the one preceding. This result may be accomplished by arranging baffles of substantially equal height in a trough 44 inclined upwardly from front to rear, as shown in the drawing, or by baffles progressively increasing in height from front to rear arranged in a horizontal trough, and by combinations of the two arrangements. In any case, the increase in effective height of the baffles is such that each baffle 46 will catch and deflect the proper amount of air for the 10 space between it and the preceding baffle.

While in the drawings the baffles 46 are illustrated as equally spaced from one another, and the vertical distance that each baffle overlaps the baffle immediately ahead of it is uniform throughout the longitudinal extent of trough 44, it is apparent that the baffles may be spaced at different distances one from the other and the overlapping distance of successive baffles may be varied in accordance with the amount of air it 20 is desired to intercept and introduce into different areas considered longitudinally in the firebox.

Whatever be the speed or force of the passing air stream, a generally uniform inflow of air results along the baffled inlets, defined by troughs 44 and spaced baffles 46, of plenum chamber 40 and, accordingly, air at generally uniform static pressures is delivered through inlets 20, 22, 26 and 28. Since the suction effect on the rearwardly directed openings 26 and 28 is eliminated, the resultant negative pressures prevailing in firebox 2 become substantially lower for proper air flow and a more uniform air distribution through all the inlets prevails.

It is apparent that casing 42 structures may be formed of sheet metal simply by welding together a bottom sheet 53, front, rear, and side sheets 54, 56 and 58, respectively, adding troughs and baffles constructed generally in accordance with the prior patent (supra), and subsequently installing, by obvious mechanical expedients the entire unit on the type of locomotive for which the unit was proportioned. Before installation of the unit, the flash guards customarily outside side inlet tubes 22 may be removed since the chamber 45

and casing constitute complete flash protection.

The invention is not limited to the specific structure detailed above but is intended to cover the modifications and adaptations within the scope of the following claims.

I claim:

1. In an oil burning locomotive having, in the lower rear portion thereof front, rear, side and bottom walls, an oil burner encased within said walls, each of said walls having air openings therethrough with outwardly disposed inlet ends for feeding air inwardly to said oil burner, a casing surrounding the above-mentioned walls of said lower rear portion and spaced outwardly therefrom whereby to form a plenum chamber common to said inlet ends and whereby to shield the inlet ends from the passing airstream to which they otherwise would be exposed when the locomotive is in forward motion, and means at the sides of said casing and respectively adjacent each side of the locomotive for admitting air to said plenum chamber.

2. The combination claimed in claim 1, said means each comprising an L-shaped trough extending longitudinally of the fore-and-aft direction of the locomotive, said trough having an open top communicating with the atmosphere and an open inner side communicating with said chamber.

VAUGHN MANSFIELD.
